CLAIM

What is claimed is the ornamental design for a case for dental apparatus, as shown and described.

DESCRIPTION

FIG. 1 is a front and left perspective view of a first embodiment of a case for dental apparatus in an open position;

FIG. 2 is a front view thereof;

FIG. 3 is a front and left perspective view thereof in a closed position;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof;

FIG. 10 is a front and left perspective view of a second embodiment of a case for dental apparatus in an open position;

FIG. 11 is a front view thereof;

FIG. 12 front and left perspective view thereof in a closed position;

FIG. 13 is a front view thereof;

FIG. 14 is a rear view thereof;

FIG. 15 is a left view thereof;

FIG. 16 is a right view thereof;

FIG. 17 is a top view thereof;

FIG. 18 is a bottom view thereof;

FIG. 19 is a front and left perspective view of a third embodiment of a case for dental apparatus in an open position;

FIG. 20 is a front view thereof;

FIG. 21 is front and left perspective view thereof in a closed position;

FIG. 22 is a front view thereof;

FIG. 23 is a rear view thereof;

FIG. 24 is a left view thereof;

FIG. 25 is a right view thereof;

FIG. 26 is a top view thereof; and,

FIG. 27 is a bottom view thereof.

The broken lines in the drawings are included for the purpose of illustrating portions of the case that form no part of the claimed design.
